By his Attorney George E. Heinricke

UNITED STATES PATENT OFFICE.

PHILIP GADESKI, OF MYSTIC, IOWA.

RAILROAD-SWITCH.

1,358,196.

Specification of Letters Patent.

Patented Nov. 9, 1920.

Application filed May 1, 1920. Serial No. 378,052.

To all whom it may concern:

Be it known that I, PHILIP GADESKI, a citizen of Poland, residing at Mystic, county of Appanoose, and State of Iowa, have invented certain new and useful Improvements in Railroad-Switches, of which the following is a specification.

This invention has for its object the provision of means whereby the tongue and point of a railway switch may be moved so as to divert a train from one track to another by its passage over the track slightly in advance of the switch.

A further object is to provide means which automatically reset themselves after the passage of the train, the position of the switch point being indicated by signals as is usual.

A further object being to provide means whereby the mechanism may be rendered inoperative at any desired time.

These and other like objects are attained by the novel construction and combination of parts hereinafter described and shown in the accompanying drawings, forming a material part of this disclosure, and in which—

Figure 1 is a plan view of a track section showing a tongue and point and indicating the application of the invention.

Fig. 2 is a longitudinal sectional view taken on line 2—2 of Fig. 1.

Fig. 3 is a similar longitudinal sectional view taken on line 3—3 of Fig. 1, and

Fig. 4 is a front elevational view showing one of the operating devices.

Referring to the drawings in detail, the numeral 10 indicates one of the running rails and 11 the other, the latter rail being bent outwardly into the curve 12, the switch point 14 being also curved in conformity with a fixed curved rail 15, secured to the other portion 16 of the straight track rail 11, and after passing the space for the wheels, aligns with the point 17.

Both switch points 14 and 17 are securely bolted to brackets 18 standing up from a transversely disposed bar 19 passing under the rails and provided with an elongated slot 20, through which extend pins 21 and 22, which limit the motion of the bar, and therefore of the switch and points.

Arranged adjacent to the track, on both sides thereof, are track-side devices, each consisting of casing elements 24, provided with rigidly secured covers 25, having pro-

jections 26, arranged midway in their length, these projections being fitted to receive stems 27, extending downward from arcuately curved caps 28, fitted to the sides of the casings and supported by pairs of 60 bent flat springs 29, the ends of which rest upon the covers 25, their center portions extending upward within the longitudinal recesses 30, the springs normally holding the caps in a raised position.

Extending out from one side of the caps are fixed pins 31, the same being operatively engaged in slots having a straight portion 32, and an angular portion 33, joined at their upper ends, the angular portion terminating in a recess 34, the slots being formed in levers 35, also having longitudinal slots 36, at their ends receptive of fixed pins 37, extending from the sides of the casings 24.

The opposite ends of the levers 35 are pivoted by pins 38 to levers 39, fulcrumed on pins 40, in brackets 41, the levers being provided with offset operating handles 42, by which they may be readily manipulated, and it will be obvious that upon drawing 80 the levers in one direction, the pins 31 are forced into the angular slots 33, thereby depressing the caps 28, and thus providing means whereby the device may be rendered inoperative.

Slidably arranged longitudinally within the casings 24 are bars 44, having diagonally disposed profiles at one end, and terminating in projections 46 to which is attached one end of coiled tension springs 47, 90 the other ends being engaged in eyes set in the casing, while the opposite ends 48 of the bars are formed diagonally in a plane at a right angle from the angular elements 45.

The elements 48 are adapted to make contact with the similarly beveled ends 49, of the transverse bar 19 so that as the bars are moved in either of the housings, sliding motion is conveyed to the bar 19, which is 100 further provided with V shaped recesses 50, near each end, upon opposite sides, in which are engageable detents 51, normally pressed into operative position by the flat springs 52, thereby holding the bar 19 in either of 105 its adjusted positions.

Also one end 53 of the bar 19 is formed with rack teeth 54 engageable with the teeth of a gear 55, this gear being mounted upon a standard 56, held in an extension 57 of one 110

of the casings 24, the standard 56 having at its upper end a pair of signals 58, disposed at right angles one to the other and which are obviously rotated by movement 5 of the bar 19.

In operation, the parts having been assembled as indicated, and a train passing along the track from the left to right, an adjustable plunger carried by the train 10 makes contact with the cap 28 of the device upon one side of the track, depressing the same against the effect of the springs 29, bringing the stems 27 into engagement with the diagonally disposed element 45 of the 15 bar 44, causing it to slide forward, while the opposite, beveled end 48 of the bar makes contact with the end 49 of the bar 19, moving the same transversely below the track-way, carrying the switch and points engaged 20 therewith, while the rack 48, rotates the standard, so that the signals 58 show the switch in an open position, permitting a train to pass along the straight track only, the bar 19 being held in engagement by the 25 detent 51 so that it is not moved inadvertently.

Conversely, a train passing in the opposite direction makes contact with the track side elements upon the opposite side of the 30 track, throwing the switch point so as to cause the train to move upon the curve, while the signals indicate the movement to be taken.

As best illustrated in Fig. 3 the device 35 may be made inoperative by a passing train by means of the manually operated levers 42 which, when raised, will draw by the intermediary of sliding levers 35 the pins 31 into recess 34 and pin 37 to the end of the 40 slot 36 so that the caps 28 to which the pins are secured will obviously be lowered.

Having thus described my invention what I claim as new and desire to secure by Letters Patent, is—

45 1. In a railway switch device, the combination with a pair of switch points, and a transverse connection therebetween, of casings placed upon opposite sides of the track, covers therefor, arcuate caps movable vertically on said covers, means for normally holding said caps in a raised position, lugs

formed with said caps extending into the exterior of said casings, bars slidably arranged in said casings, said bars having diagonal faces against which said lugs are 55 adapted to contact whereby they are moved outwardly, means for normally holding said bars in operative position, and angular elements formed at the opposite ends of said bars adapted to make contact with said 60 transverse bar whereby the switch points are thrown upon contact with train carried devices against said caps.

2. In a railway switch throwing device, the combination with the running rails, having a pair of switch points and a bar connecting said switch below said running rails, said bar having diagonally disposed ends, of track side devices comprising casings, bars slidable longitudinally therein, means 70 for holding said bars in one direction, angular elements formed with said bars at each end, one of said ends being adapted to make contact with said switch bar, arcuate caps adapted to move vertically on said casings, 75 means for holding said caps in a normally raised position, projections extending inward from said caps through said casings adapted to make contact with the other beveled surface of said bars, and means for 80 holding said switch bar in either of its adjusted positions.

3. In a railway switch device, the combination with the running rails, and switch points therein, of a transverse bar engaged 85 with said switch points below said running rails, track side devices at each side of said track, bars slidable in each of said track side devices, said bars having beveled ends, means for normally holding the bars in an 90 operative position, caps resiliently raised from said casings, said caps having elements extending into said casings adapted to make contact with one of the beveled ends of said 95 slidable bars, means for normally depressing said caps so that the movement of a passing train has no action thereon, and means actuated by said transverse bar for indicating the position of said switch points.

In testimony whereof I have affixed my 100 signature.

PHILIP GADESKI.
